United States Patent Office.

DANIEL KELLY, OF MUSKEGON, MICHIGAN.

Letters Patent No. 102,829, dated May 10, 1870.

IMPROVEMENT IN BORING BITS.

The Schedule referred to in these Letters Patent and making part of the same.

To whom it may concern:

Be it known that I, DANIEL KELLY, of Muskegon, in the county of Muskegon and State of Michigan, have invented a new and useful Improvement in Boring-Bits; and I do declare that the following is a true and accurate description thereof, reference being had to the accompanying drawings and to the letters of reference marked thereon, and being a part of this specification, in which—

Figure 1 is an elevation of my improved bit, and Figure 2 is an end view of the same.

Like letters indicate like parts in each figure.

The nature of this invention relates to an improved construction of bits for boring wood.

It consists in providing the stock of the tool with the spur commonly used in center-bits, and on the opposite side with a cutter formed of a half convolution of a screw; also, in providing the elongated point with a cutting-lip, the whole forming a more durable bit than any now in use, and easier to operate.

In the drawings—

A represents the stock of my bit, conical toward the point *a*, which is provided with a cutting-lip, *b*.

B is a spur, of the form generally attached to center-bits.

C is the cutter, which is a half convolution of a screw about the stock.

The point being provided with the cutting-lip, cuts its passage as it advances, and is not to be forced into the wood, as is the case with auger and center-bits. The point of the spur circumscribes the bore, and gauges the depth of cutter following it, while the latter being but of sufficient length to feed down the tool, and to carry back the chip, the boring is effected with the least friction and perfect truth.

It will readily be seen that this bit will last or wear longer than either the center or auger-bit, as the cutter of the former and screw-point of the latter will not permit of much filing.

The spur may be in the form of a partial convolution of a screw about the stock, if desired, or it may extend the full length of the stem.

What I claim as my invention, and desire to secure by Letters Patent, is—

A bit, having a conical point, *a*, provided with a cutting-lip, *b*, and its stock *A*, with a spur, *B*, and cutter *C*, the latter in the form of a partial convolution of a screw-thread about the stock, substantially as described.

DANIEL KELLY.
